Primary Examiner—Mitchell Siegel

(57) **CLAIM**

The ornamental design for a putting guide, as shown and described.

DESCRIPTION

FIG. 1 an end elevational view of the present invention a putting guide as shown in FIG. 3.

FIG. 2 is a side elevational view of the putting guide as shown in FIG. 3.

FIG. 3 is a top plan view of the present invention a putting guide.

FIG. 4 is a end elevational view of the putting guide shown in FIG. 3.

FIG. 5 is a top perspective view of the putting guide shown in FIG. 3.

FIG. 6 is a bottom perspective view of the putting guide shown in FIG. 3.

FIG. 7 an end elevational view of an alternate embodiment of the present invention a putting guide as shown in FIG. 9.

FIG. 8 is a side elevational view of the putting guide as shown in FIG. 9.

FIG. 9 is a top plan view of the present invention a putting guide.

FIG. 10 is a end elevational view of the putting guide shown in FIG. 9.

FIG. 11 is a top perspective view of the putting guide shown in FIG. 9.

FIG. 12 is a bottom perspective view of the putting guide shown in FIG. 9.

FIG. 13 an end elevational view of an alternate embodiment of the present invention a putting guide as shown in FIG. 15.

FIG. 14 is a side elevational view of the putting guide as shown in FIG. 15.

FIG. 15 is a top plan view of the present invention a putting guide.

FIG. 16 is a end elevational view of the putting guide shown in FIG. 15.

FIG. 17 is a top perspective view of the putting guide shown in FIG. 15; and,

FIG. 18 is a bottom perspective view of the putting guide shown in FIG. 15.
